UNITED STATES PATENT OFFICE.

CHESTER H. THORDARSON, OF CHICAGO, ILLINOIS.

TRANSFORMER.

1,259,565.

Specification of Letters Patent. Patented Mar. 19, 1918.

Application filed January 24, 1918, Serial No. 744,001. Renewed September 20, 1915. Serial No. 51,700.

To all whom it may concern:

Be it known that I, CHESTER H. THORDARSON, a citizen of the United States, and a resident of Chicago, in the county of Cook and State of Illinois, have invented certain new and useful Improvements in Transformers; and I do hereby declare that the following is a full, clear, and exact description thereof, reference being had to the accompanying drawings, and to the characters of reference marked thereon, which form a part of this specification.

This invention relates to improvements in electrical transformers and to coils for use in transformers and for other uses, and the invention consists in the matters hereinafter set forth and more particularly pointed out in the appended claims.

Among the objects of the invention is to provide a novel coil structure and arrangement for transformers designed to ventilate the coil by directing the passage of a cooling medium through determinate passages in the coil structure, and also arranged to give stability and durability to the coil structure by bracing and stiffening the windings.

The invention consists in the combination and arrangement of the parts shown in the drawing and described in the specification, and is set out in the appended claims.

In the drawings:

Figure 1 is a side elevation of a transformer embodying my improvements, showing the inclosing casing in section.

Fig. 2 is a section on the line 2—2 of Fig. 1.

Fig. 3 is a section on the line 3—3 of Fig. 6.

Fig. 4 is an enlarged side elevation of a portion of a coil embodying my invention.

Fig. 4^a is a fragmentary transverse section of the coil.

Fig. 5 is a perspective view of a few assembled laminations which make up the magnetic circuit.

Fig. 6 is a side elevation of one of the winding units composing the coil.

Fig. 7 is a transverse section on the line 7—7 of Fig. 1.

Fig. 8 illustrates one of the insulating

sheets which cover the corners of the outer units of the high tension coil on the faces adjacent to the low tension winding.

As shown in the drawings, 10 designates the casing in which the transformer is inclosed. 11 designates, as a whole, the laminated magnetic circuit structure. The detail of this structure is best shown in Fig. 5. It comprises, in the illustrated embodiment of the invention, a series of superposed thin plates of good magnetic metal, each thickness embracing a member 12 of general E shape and a straight member 13 fitted to the margins of the end and intermediate terminals 14, 15, respectively, of the member 12. The adjacent laminations, composed of the two members 12 and 13, respectively, are arranged in reverse relation with respect to each other so as to bring the straight bar portions 13 of one lamination flat against the straight portion 12 of the other lamination. This construction provides an exceedingly compact and efficient magnetic circuit structure, and one which may be readily produced and assembled. The intermediate portion 15 of the structure constitutes the core member of the magnetic circuit structure, at each side of which are provided openings 16, 16 (Fig. 5) to receive the parts of the coils or windings wound about said core member.

18 designates, as a whole, the primary winding of the coil made up of the units 19, 19 and 20, 20 designate the two units of the secondary winding. The units of the primary winding may be connected together in series or in multiple, and the units of the secondary winding may be likewise connected in series or in multiple.

The said winding units herein shown have the form of a generally rectangular ring, with the outer corners rounded, as best shown in Figs. 2 and 6. They are arranged side by side around the core member 15 of the magnetic circuit structure. The four or more units which make up the primary coil are bound together by insulating tapes or bands 23 wound about the side members of the rectangular rings, as best shown in Figs. 1, 2, 3 and 6. The corners of the outer units 19 at their outer sides are

insulated from the units of the secondary coil by means of separately applied mica or other suitable insulating plates 24 (Figs. 2 and 8) which may extend at their outer edges beyond the edges of the units, and thereby render it unnecessary to close the plates over the corner edges of the units. Said insulating plates may be provided with marginal projections 24^a to engage under the adjacent ends of the tapes 23 or other form of insulation used to thereby provide good insulating joints between said parts.

The units 20 of the secondary coil are confined between said winding tapes 23 and the side walls of the openings 16 through which the members of the units extend and are spaced from the adjacent units of the primary winding by the tapes 23. This construction provides means for reliably holding the windings or coils in proper relation to each other and to the magnetic circuit structure, and also provides means to space the secondary units from the adjacent units.

The laminations of the magnetic circuit structure are held in place by means of bolts 25, 25 which extend through corresponding members of angle bars 26 arranged in the angles between the sides of the magnetic circuit structure and the windings, said bolts being located at the upper and lower ends of said magnetic circuit structure. Other bolts extend through the other members of the angle bars and above and below the magnetic circuit structure, and said latter bolts are each provided at each end with inner and outer nuts 29, 30, respectively, so as to serve as spacing means to prevent the members of the angle bars, through which the latter bolts extend, being pressed inwardly against the winding units 20. In order to prevent the laminations of the magnetic circuit structure from being laterally displaced relatively to the members of the frame thus formed by said angle bars and bolts, the upper ends of the laminations are notched at 31 to engage the bolts 25.

Certain of the primary winding units are spaced by means providing between the same passages for the flow of a cooling liquid, as oil or other insulating liquid contained within the casing 10 and in which the transformer is submerged. The spacing means may also, and as herein shown, do serve as means to brace or stiffen the coil. The passages or ways are herein shown as formed between the upper and lower pairs of directing members 35, 35. One end of one member of each pair extends to one side of the unit and is turned downwardly, as shown at 36, while the opposite end of the other member of the pair extends to the opposite side of the unit and is curved upwardly as shown at 37. This is repeated

at the upper side of the unit, the parts having a generally symmetrical relation with respect to each other at the upper and lower sides of the opening for the core member. As a result there is provided between the strips of each pair a transverse way or conduit for cooling fluid between certain of the winding units, with one terminal thereof arranged to receive a rising fluid, and with the other terminal thereof arranged to direct the fluid which passes through the conduit upwardly. The cooling fluid is returned to the bottom of the casing between the frame and the casing so as to thereby bring the heated fluid into contact with the relatively cool walls of the casing, to thereby absorb the heat of said fluid. The deflection of the strips 35 at their ends has also the further function of increasing their bracing efficiency to stiffen the coil. This is due to the fact that said curved ends of the strips intersect a greater number of turns of the unit than otherwise, and in angular relation to the winding layers. The said strips 35 extend transversely through the magnetic circuit structure and beyond the same at their ends, as most clearly shown in Fig. 6. The lower strip of each pair is provided with a branch 38 adjacent to the curved end 36 of the other strip of the pair and said branches extend transversely across the space between the members of each pair and extend at their upper ends beyond the lower ends of the adjacent curved terminals 36. This arrangement provides means for rigidly bracing the members of the units which extend through the magnetic circuit structure against lateral displacement, which tends to occur when the coils are energized. By reason of the fact that the side members of the units, or those located at the sides of the magnetic circuit structure are transversely overlapped at their end portions by the ends of the strips 35, and of the fact that the flat wire is very stiff in the direction of its width, the turns of the units at the sides thereof are also well braced against lateral displacement.

The strips 35, thus arranged, provide means to direct the cooling fluid between certain of the units in prescribed paths. The circulation of the fluid within the casing through the conduits or ways between the winding units may be effected by the differential temperatures of the fluid, the hottest fluid naturally rising and the cooler fluid naturally seeking the lower part of the casing, or may be otherwise effected, as desired. The said directing members 35 are herein shown as attached to the winding units by means of tapes 39 which partially surround said members and overlap at their margins the inner and outer margins of the members

of the winding units across which said directing members extend.

The said winding units of the high and low tension coils are alike, except as to the 5 dimensions of the flat wires 40 forming the same. As a further and separate improvement the said units are made as follows:

Between each turn of each winding is interposed two or more thin sheets 41 of insulating material, such as paper. These sheets 10 of insulating material are made wider than the flat wires of the windings and, therefore, extend laterally beyond the margins of said wires, as shown in Fig. 4^a, so as to insulate 15 each turn of the winding from an adjacent turn. In practice, I have found that a projection of the sides of the strips 41 beyond the wires 40 of one thirty-second to three sixty-fourths of an inch is efficient for transformers of the size most often used. These strips of insulating material are made as 20 thin as the physical conditions will permit, having regard to the ordinary handling thereof, and the winding of the same in the 25 winding unit. For instance, I have used in high tension coils or windings insulating sheets of less than one-thousandth of an inch in thickness. I have found that a single 30 thickness of insulating strip as, for instance, paper, is unreliable by reason of the fact that flaws occur in the paper and impair the insulating efficiency thereof, and that to 35 avoid such defects with a single strip of paper or insulating material, it is necessary to provide a strip of such thickness as to 40 render the coil structure excessively large and heavy. By using two or more thin strips of paper, or like material, (two being usually sufficient) the chances of flaws in 45 the paper registering so as to produce a through opening in the superposed strips through which one turn may be short circuited on the other is so small as to be negligible. As a result of this construction I am 50 enabled to produce a highly efficient insulation between the turns of the windings, and at the same time reduce the thickness of the multiple sheet insulation as compared to a single strip heretofore employed. I have 55 found, in practice, that a coil or winding unit of a given capacity may be reduced in dimensions substantially one-half of the dimensions of the prior construction where a single efficient insulating sheet or strip between the turns is employed. The construction 60 is not only compact, but is also of less relative weight as compared to the prior transformer constructions of equal efficiency, it being possible to reduce the weight at least one-half. This is partially due to the 65 fact that the reduction of the weight and dimensions of the coil winding permits of a corresponding reduction of the weight and size of the magnetic circuit structure.

Moreover, a multi-sheet insulation is far 65 superior in efficiency to any practical single sheet insulation heretofore used. After the units are wound, they may be boiled in a suitable insulating liquid, such as paraffin, to increase the insulating efficiency of the paper, and to stiffen the winding structure. In order to brace or stiffen the first few or inner turns of the winding units, the insulating strip for the first few turns may be 70 made of a relatively thick insulating strip, 75 applied by hand to the winding form, inasmuch as the pressure difference between the inner turns is not great.

The transformer herein shown is a step-down transformer but it will be understood 80 that the same principles of construction are equally well adapted to a step-up transformer. I have not herein shown the terminals for the coils, it being understood that in a step-down transformer the primary 85 coils are connected to the energizing circuit, and that the terminals of the secondary coils are connected to the distributing circuit. In a step-up transformer this adjustment will be reversed. Moreover, the primary and 90 secondary may be balanced. In practice, it is convenient to connect the adjacent windings of the primary at their inner circumference, so that the leads to the exterior of the coil may be taken from their outer 95 circumferences. The terminals of the side units, however, may conveniently be taken from either the inner or the outer circumference of the units. I have not herein shown the terminals but it will be understood 100 that the wiring connection to the coil may conform to any standard transformer practice.

The means for insulating the coil conductor strips or turns from each other is 105 not herein claimed, the same being made the subject of an application filed by me on the 30th day of June, 1913, Serial No. 776,521, divided from the present application.

It will be understood that the structural details of the device may be somewhat varied within the spirit and scope of the invention, and that the invention is not limited to the details shown except as hereinafter made the subject of specific claims or as imposed by the prior art.

I claim as my invention:—

1. In an electrical transformer, the combination with a plurality of spaced winding units of a coil, each composed of a spirally wound strip with an insulating element between the turns thereof, of fluid directing and winding unit bracing strips between the units arranged in upper and lower pairs to 120 form ventilating fluid passages, one strip of each pair being directed downwardly at its end and the other strip of each pair directed 125

upwardly at its end and said ends of the strips extending transversely across the edges of the winding layers.

2. In an electrical transformer, the combination with a magnetic circuit structure, embracing a core member, a primary and a secondary coil surrounding the core member, each composed of a plurality of flat wire winding units suitably spaced and supported on the circuit structure, certain of the primary winding units being spaced by fluid directing and bracing strips extending across the parts of the coil included in the said circuit structure, said strips extending upon the side parts of the winding units at the sides of the circuit structure and there turned at angles to the bodies of the strip to thereby brace the turns of the winding units at the ends of said side parts, and to direct the cooling fluid in definite paths between the units of the coil structure.

3. In an electrical transformer, the combination with a magnetic circuit structure, embracing a core member, a primary and a secondary coil surrounding the core member, each composed of a plurality of flat wire winding units suitably spaced and supported on the circuit structure, certain of the primary winding units being spaced by bracing strips extending across the parts of the coil included in said circuit structure, said strips extending upon the side parts of the winding units at the sides of the circuit structure to thereby brace the turns of the winding units at the ends of said side parts, certain of the strips being provided with bracing and cooling fluid deflecting branches extending transversely over the turns of the adjacent sides of the winding units.

4. In an electrical transformer, the combination with a plurality of spaced winding units of a coil, of fluid directing strips between the same arranged in upper and lower pairs to form passages, one of the strips of each pair being directed downwardly at its end and the other strip of each pair directed upwardly at its end, one of the strips of each pair being provided with branches which extend across the space between said strips and transversely to the turns of the adjacent side of the winding unit.

5. In an electrical transformer, the combination with a plurality of spaced winding units of a coil, of fluid directing and coil bracing strips between the units and arranged adjacent to the margins of the upper and lower sides of the coil to form between them passages to direct a cooling liquid between the units, and means for fastening the strips in place, comprising tapes partially surrounding the strips and extending outwardly upon and overlapping the members of the winding units and fastened thereto.

6. An electrical transformer comprising a

laminated magnetic circuit structure, embracing a core member, primary and secondary coils surrounding said core member, and extending laterally from the sides of the magnetic circuit structure, angle bars in the angles between the circuit structure and the coils, with clamping bolts extending between corresponding members of the angle members to clamp the laminations of the circuit structure together, and spacing means extending between the other members of the angle bars to space the said latter members from the coil structures.

7. An electrical transformer comprising a laminated magnetic circuit structure embracing a core member, primary and secondary coils surrounding said core member and extending laterally from the sides of the magnetic circuit structure, angle bars in the angles between the circuit structure and the coils, with clamping bolts extending between corresponding members of the angle members to clamp the laminations of the circuit structure together, interlocking connections between said bolts and said laminations to hold the laminations from displacement with respect to the angle bars, and spacing means extending between the other members of the angle bars to space said latter members from the coil structures.

8. An electrical transformer comprising a laminated magnetic circuit structure, embracing a core member, primary and secondary coils surrounding said core member and extending laterally from the sides of the magnetic circuit structure, angle bars in the angles between the circuit structure and the coils, with clamping bolts extending between corresponding members of the angle members to clamp the laminations of the circuit structure together, and spacing means extending between the other members of the angle bars, the ends of the laminated magnetic circuit structure being notched, and the clamping bolts engaging said notches.

9. An electrical transformer comprising a laminated magnetic circuit structure, embracing a core member, primary and secondary coils surrounding said core member and extending laterally from the sides of the circuit structure, and a frame for binding together the coil and the circuit structures comprising angle bars having members pressed against the laminated circuit structure, with clamping bolts extending between the same, and having other members abreast of and spaced from the coil structure, and spacing means extending between the said other members of the angle bars.

10. An electrical transformer comprising a laminated magnetic circuit structure, embracing a core member, primary and secondary coils surrounding said core member and extending laterally from the sides of

the circuit structure, and a frame for binding together the coil and circuit structures comprising angle bars having members pressed against the laminated circuit structure, with clamping bolts extending between the same, and having other members abreast of and spaced from the coil structure, and spacing means extending between the said other members of the angle bars, 10 said primary and secondary coils embracing winding units having means to insulate

them from each other and having spaces therebetween for the flow of a cooling liquid.

In testimony, that I claim the foregoing as my invention I affix my signature in 15 the presence of two witnesses, this 20th day of January, A. D. 1913.

CHESTER H. THORDARSON.
